CLAIM

The ornamental design for a golf cart carried open umbrella holder, as shown and described.

DESCRIPTION

FIG. 1 is a front elevational view of a golf cart carried open umbrella holder showing my design;

FIG. 2 is a right side elevational view thereof;

FIG. 3 is a left side elevational view thereof;

FIG. 4 is a top plan view thereof with the lower fastener omitted for purposes of clarity;

FIG. 5 is a bottom plan view thereof with the upper fastener omitted for purposes of clarity; and

FIG. 6 is a rear elevational view thereof.

The umbrella and parts of a golf cart shown in broken lines are for illustrative purposes only.
